(57) **CLAIM**

The ornamental design for a pillar array disc brakes, as shown and described.

DESCRIPTION

FIG. 1 is a top perspective view of a disc brake pillar array having a unique configuration of the present design;

FIG. 2 is a bottom perspective view of a disc brake pillar array having a unique configuration of the present design;

FIG. 3 is a cross-sectional side view of a disc brake pillar array having a unique configuration of the present design taken along line 3—3 in FIG. 1;

FIG. 4 is a top view of a disc brake pillar array having a unique configuration of the present design;

FIG. 5 is a bottom view of a disc brake pillar array having a unique configuration of the present design;

FIG. 6 is a side view of a disc brake pillar array having a unique configuration of the present design; and,

FIG. 7 is a cross-sectional top view of a disc brake pillar array having a unique configuration of the present design taken along line 7—7 in FIG. 1.
